UNITED STATES PATENT OFFICE.

ARILD M. BRENN, OF CHICAGO, ILLINOIS, ASSIGNEE, BY MESNE ASSIGNMENTS, TO
W. H. MINER, INC., A CORPORATION OF DELAWARE.

SIDE BEARING FOR RAILWAY CARS.

Application filed February 9, 1923. Serial No. 617,943.

This invention relates to improvements in side bearings for railway cars.

One object of the invention is to provide an efficient side bearing comprising few, simple and inexpensive parts, including an anti-friction element, and a rack and gear for effecting return of the anti-friction element to central position, wherein means is provided to eliminate the binding of the teeth of the rack and gear when the device is operated under load.

Another, and more specific object of the invention is to provide a side bearing of the type referred to, comprising an anti-friction roller element, supported from the body bolster of a car, a rack fixed to the body bolster and a gear meshing with the rack and loosely associated with the roller, with the weight of the gear supported by the roller element in such a manner, that the gear is normally adapted to rotate in unison with the roller element, due to the friction between the parts during return movement of the body and truck bolsters to aligned position, thereby insuring the proper return and centering of the parts, but with the parts so designed that the gear is adapted to slip with respect to the roller element, should the teeth of the rack and gear fail to register properly, when the device is operating under load, and permit the teeth to register and thereby avoid crushing of the same.

Other objects and advantages of the invention will more clearly appear from the description and claims hereinafter following.

In the drawing, forming a part of this specification, Fig. 1 is a transverse vertical sectional view through the ends of the body and truck bolsters of a railway car showing my improvements applied thereto. Fig. 2 is a vertical sectional view corresponding substantially to the line 2-2 of Fig. 1. And Fig. 3 is a view similar to Fig. 1 illustrating a modified form of the invention.

In Figs. 1 and 2 of said drawing, the upper portion or top flange of the truck bolster is indicated by 10 and the lower portion or flange of the body bolster is indicated by 11.

The bearing, as shown in Figs. 1 and 2 illustrating the preferred form of the invention, consists, broadly, of a housing A, adapted to be secured to the body bolster; an anti-friction roller element B, within the housing A; a rack C, formed integral with the housing A; and a gear D meshing with

the rack C and loosely associated with the roller element B.

The housing or retaining member A, as shown, comprises a casting of generally hollow box like form, having a top wall 12, vertical depending spaced side walls 13-13, vertical depending end walls 14-14 and laterally projecting securing flanges 15-15, by which the retaining member is adapted to be secured to the body bolster, as by rivets 16-16. The retaining member A is provided on the interior thereof with the longitudinally extending rack C formed integral with the top wall 12, and upper bearing surfaces consisting of a pair of longitudinally extending spaced plates 17-17, located on opposite sides of the rack C and secured to the lower side of the top wall 12, as by rivets 18-18.

The anti-friction roller element B comprises a pair of spaced anti-friction rollers 19 and 20, the roller 19 being formed with a laterally extending integral concentric stub shaft portion 21, on which the roller 20 is mounted. At the outer end the stub shaft 21 is reduced in diameter as indicated at 22, thereby providing an intermediate bearing portion 23 of slightly greater diameter, adapted to receive the gear D. The reduced end portion 22 of the stub shaft 21 is adapted to tightly engage the roller 20, the roller 20 being held in place by a driving fit, so that the rollers 19 and 20 will always rotate in unison. The anti-friction roller element B is held in assembled relation with the housing A by a pin 24 extending through the axial bore 25 of the roller element B and provided with enlarged cylindrical end portions 26 and 27 loosely received for vertical play in longitudinally extending slots 28 in the side walls 13 of the housing A. The cylindrical portion 26 of the pin is formed integral therewith, and the cylindrical portion 27 is in the form of a collar, held in position by the end of the pin being upset as indicated at 29.

The gear D is provided with teeth 30 adapted to mesh with the teeth 31 of the rack C and has formed therein a central bore 32 of slightly larger diameter than the bearing portion 23 of the stub shaft 21, to loosely engage the same for a purpose hereinafter described.

In Figs. 1 and 2 of the drawing, the body and truck bolsters are shown as separated,

with the parts of the anti-friction bearing in normal position. The anti-friction roller element B, is shown, as supported by the truck bolster, with the lower sides of the 5 rollers 19 and 20 bearing on the upper surface of the flange 10, and the upper sides thereof slightly spaced from the lower faces of the bearing plates 17—17. the enlarged portions 26 and 27 of the pin 24 spaced from 10 the upper and lower walls respectively of the slots 28. In this position of the parts the gear D loosely engages with the rack C, and is supported on the upper side of the bearing portion 23, with the wall of the 15 bore 32 at the lower side thereof spaced slightly from the lower side of the bearing portion 23, and the entire weight of the gear carried by the roller element. As the bearing portion 23 of the stub shaft and the 20 bore 32 are of relatively large diameter with reference to the size of the gear, large frictional contact surfaces are provided therebetween, and when the weight of the gear is supported by the roller element, there will 25 be sufficient friction to cause the gear to rotate in unison with the roller element, while the roller element travels on the surface of the truck bolster during the return movement of the body and truck bolsters, 30 causing the gear teeth to travel on the rack and thereby insuring the proper return and centering of the parts.

In the operation of my improved roller side bearing as shown in Figs. 1 and 2, as 35 the body and truck bolsters approach each other and move in horizontal directions relatively to each other, with the lower sides of the rollers 19 and 20 bearing on the upper surfaces of the truck bolster the plates 40 17—17 will be brought into engagement with the upper sides of the rollers, there being sufficient play of the enlarged ends of the pin 24 in the slots 28 to permit of this movement. During this operation, the gear 45 D will also approach the rack C, bringing the teeth thereof in a closer mesh, there being sufficient play between the teeth to permit of this movement. Should the teeth of the gear be so positioned as not to register 50 properly with the teeth of the rack, the friction between the gear and the bearing portion 23 will be overcome and the gear slip on the bearing portion 23 of the stub shaft so as to permit the teeth thereof to 55 properly engage with the rack teeth, thereby avoiding crushing of the same.

In the modification shown in Fig. 3, the top flange of the truck bolster is indicated by 110 and the bottom flange of the body bolster is indicated by 111. The housing A' is 60 in all respects similar to the housing A of the preferred form of the invention and comprises, top wall 112, end walls 113 and side walls 114. The top wall 112 has the 65 rack C' formed integral therewith and is

also provided with bearing plates 117 secured by rivets 118. Within the housing A' supported by the truck bolster, and provided with the pin 124 having enlarged ends working in the slots 128, formed in the side 70 walls 114, is the anti-friction roller element B', in all respects similar to the element B of the preferred form, with the exception that the bearing portion 123 between the rollers, and on which the gear is mounted, is 75 provided with a roughened surface in the form of peripheral clutch teeth 140.

The gear D' is loosely mounted on the bearing portion 123 and has the bore 132 thereof provided with interior clutch teeth 80 141 adapted to engage with the clutch teeth 140 to act in the manner of a clutch, to cause the parts to normally rotate in unison, but to permit relative movement of the parts by the teeth slipping over each other, should 85 the teeth on the gear 130 be so positioned as not to register properly with the teeth 131 on the rack when the device is under operating load. In this connection, it is pointed out that the rack and gear mesh 90 with sufficient looseness to permit the proper amount of upward movement of the gear D' relatively to the roller B', to allow the clutch teeth 140 and 141 to ride over each other without causing any binding between 95 the gear teeth 130 and 131.

The operation of the modified form of the invention, shown in Fig. 3 is somewhat similar to that described in connection with the preferred form, and a further description thereof is therefore not deemed necessary.

From the preceding description it will be seen that in the side bearing constructed in accordance with my invention, all binding 100 between the gear teeth and the rack teeth, due to improper registration, is eliminated and crushing of the teeth under load is positively prevented.

I have herein shown and described what 110 I now consider the preferred manner of carrying out the invention, but the same is merely illustrative and I contemplate all changes and modifications that come within the scope of the claims appended hereto. 115

I claim:

1. In a side bearing for railway cars, the combination of a retaining member provided with a rack, a roller within the retaining member, said roller being provided with an 120 axially extending cylindrical supporting portion, and a complete circular gear meshing with said rack and resting on and loosely surrounding said cylindrical supporting portion and adapted to slip circumferentially relative thereto to permit the rack teeth to mesh properly with the gear teeth without turning the roller and also adapted to rotate with said roller.

2. In a side bearing for railway cars, the 130

combination with a retaining member, provided with a rack; a roller element within said retaining member and bearing on the truck bolster, said roller element being provided with a supporting portion; a gear meshing with said rack and loosely mounted on said supporting portion of said element; and inter-engaging clutch means on said gear and supporting portion.

10 3. In a side bearing for railway cars, the combination with a retaining member provided with a rack; of a roller element within the retaining member, said roller element being provided with an axially extending cylindrical supporting portion, said supporting portion being provided with teeth; and a gear meshing with said rack and mounted on said cylindrical supporting portion, said gear being provided with teeth normally engaging with the teeth of said supporting portion.

15 4. In a side bearing, the combination with body and truck bolsters, said body bolster having a rack fixed thereon; a single anti-friction element interposed between said bolsters and adapted to be normally supported on said truck bolster and to have rolling en-

gagement therewith, and adapted to bear against said body bolster, said anti-friction element being provided with a reduced portion; and a gear element carried directly by the reduced portion of said anti-friction element and surrounding the same, said gear member meshing with the rack of the body bolster, said gear member having means 35 inter-engaging with the reduced portion of said anti-friction member to effect a relatively fixed connection between said gear member and reduced portion under normal conditions to assure rotation of said gear 40 and anti-friction element in unison in the same direction as a unit, to position said anti-friction element dependent upon movement of said body and truck bolsters relatively to each other, said connection permitting relative movement of said gear member with reference to the reduced portion of said anti-friction element when pressure in excess of normal is applied to said gear member.

20 In witness that I claim the foregoing I 50 have hereunto subscribed my name this 3rd day of February, 1923.

ARILD M. BRENNE.
